UNITED STATES PATENT OFFICE.

FREDERICK SKELTON, OF BURLINGTON, ONTARIO, CANADA.

REINFORCED D-HANDLE.

1,240,503.

Specification of Letters Patent. Patented Sept. 18, 1917.

Application filed February 19, 1917. Serial No. 149,545.

To all whom it may concern:

Be it known that I, FREDERICK SKELTON, a subject of the King of Great Britain, residing at Burlington, in the Province of 5 Ontario and Dominion of Canada, have invented certain new and useful Improvements in Reinforced D-Handles, of which the following is a full, clear, and exact description.

10 This invention relates to D-handles for shovels, spades and other tools, and more particularly to wooden handles consisting of a haft or stem having diverging arms at its upper ends between which arms is inserted a grip-bar.

20 The primary object of the invention is to provide a reinforcement for a handle of this character that will protect the portions of the handle which might become loose, worn or broken, due to the rough usage to which a handle of this character is ordinarily subjected.

25 Other objects of the invention is to provide a reinforcement which is composed of a minimum number of pieces, which is economical to manufacture and which will rigidly unite the parts of the wooden handle.

30 With these and other objects in view, the invention contemplates a reinforcement for each arm, which comprises a ferrule or ring for engaging over the end of the grip-bar, a cap for protecting the upper end of the arm, and reinforcing strip which extends down the outer face of the arm for a considerable distance. The three parts of the metallic reinforcement are preferably integral and formed from a blank of sheet metal, having two projecting ears which, 35 when one end of the blank is cupped to form the cap, are bent to form a closed ring with the edge of the cupped portion.

40 In the accompanying drawings:

45 Figure 1 shows in elevation one embodiment of the invention, the view being partially in section;

Fig. 2 shows the completed metallic reinforcement ready for assembling; and

50 Fig. 3 shows the blank from which the metallic reinforcement is formed.

55 In the drawings, the wooden haft or stem to which a shovel, spade or other tool, is secured, is indicated 1. The upper end of this stem is bifurcated to provide two arms 2 and 3, which diverge forming a yoke or fork. At a point just below the beginning

of the bifurcation in the stem, a rivet 4 passes through the stem to prevent it from splitting. Inserted between the upper ends of the two arms 2 and 3 is a grip-bar 5. 60

The wooden handle described is reinforced by metallic reinforcements, each consisting of a ring or ferrule 6, which fits over the end of the grip-bar, the grip-bar being of slightly reduced diameter at its end, as 65 indicated at 5' so that the ferrule or ring 6 is substantially flush with the surface of the grip-bar. The upper ends of each of the arms 2 and 3 is protected by a cap which is formed integral with the ring 6, the cap 70 fitting over and entirely covering the upper end of the arm. A reinforcing strip 8 forms an extension of the cap 7, the strip 8 being curved, as is also the cap 7, to fit snugly against the arm. Rivets 9 passing through 75 the arms secure the lower ends of the strips 8 to the arms. An elongated rivet or rod 10, which passes through the arms, grip-bar and caps, rigidly unites these parts and also serves to hold the grip-bar in place. The 80 reinforcing strips 8 extend sufficiently down the arms to prevent them from splitting or cracking and also to protect them from wear, and since the cap portion completely covers the upper ends of the arms 85 and the rings 6 hold the grip-bar in place, it will be seen that the construction described thoroughly reinforces a wooden D handle in a simple, but efficient manner.

The ring 6, cap portion 7, and reinforcing 90 strip 8 are preferably constructed from a single piece of sheet metal, and in Fig. 3 of the drawing a blank from which this metallic reinforcement is made, is shown. This blank consists of an upper portion 10' which 95 is somewhat semi-circular in form, a lower portion 11 which is of less width, and two projecting ears or lugs 12. In forming the reinforcement, this blank is first stamped and the upper portion 10' thereof is cupped 100 to form the cap 7, the lower portion 11 being simultaneously curved so as to fit snugly against the outer face of the arm. Simultaneously with the cupping of the upper portion 10', the projecting ears or lugs 12 are 105 bent bodily through substantially a right angle, and will assume the position shown in dotted lines in Fig. 2. These lugs or ears are then bent and their ends are joined together as at 13, so that they will form 110 with the rim or edge 14 of the cupped portion or cap 7, the ring or ferrule 6 which has

been described. The joining of the ends of the ears or lugs 12 is preferably accomplished by a welding, although it may be done in any other desired manner. The 5 finished metallic reinforcement is shown in full lines in Fig. 2, and it should be noted that a space is provided between the lower portion of the ring and the cap and reinforcing strip which permits the reinforcement to be slipped over the upper end of the 10 arms when the parts of the handle are assembled.

I claim:

1. A D-handle comprising a wooden stem 15 having diverging arms and a grip-bar inserted therebetween, and a metallic reinforcement for each arm comprising a ring fitting over the end of the grip-bar, a cap-piece concealing the upper end of the arm and a reinforcing strip secured to the outer 20 face of the arm.

2. A D-handle comprising a wooden stem having diverging arms and a grip-bar inserted therebetween, and a one piece metal-

lic reinforcement for each arm comprising 25 a ring fitting over the end of the grip-bar, a cap-piece concealing the upper end of the arm and a reinforcing strip secured to the outer face of the arm.

3. A D-handle comprising a wooden stem 30 having diverging arms and a grip-bar inserted therebetween, and a one piece metallic reinforcement formed of sheet metal for each arm comprising a ring fitting over the end of the grip-bar, a cap-piece concealing 35 the upper end of the arm and a reinforcing strip secured to the outer face of the arm.

4. A blank for forming a metallic reinforcement for D-handles comprising a strip 40 of sheet metal having a semi-circular portion adapted to be cupped to form a cap and ears projecting downwardly from said semi-circular portion adapted, when bent, to form with the edge of the cupped portion a 45 closed ring.

In witness whereof, I subscribe my signature.

FREDERICK SKELTON.
